UNITED STATES PATENT OFFICE.

HARRY W. BROADY, OF BAYSIDE, NEW YORK, ASSIGNOR, BY MESNE ASSIGNMENTS,
TO AMERICAN BALSA WOOD CORPORATION, A CORPORATION OF NEW YORK.

BUILT-UP PANEL.

Application filed June 14, 1921. Serial No. 477,475.

To all whom it may concern:

Be it known that I, HARRY W. BROADY, a citizen of the United States, and a resident of Bayside, borough of Queens, county of 5 Queens, and State of New York, have invented certain new and useful Improvements in Built-Up Panels, of which the following is a specification.

This invention relates to improvements 10 in built-up wooden panels coated with plastic material and methods of building same.

One of the objects of this invention is the provision in a coated wooden panel of a keying groove for the plastic material 15 formed of a plurality of communicating groove sections whereby the contraction and expansion of the material in dry and wet conditions respectively will be compensated for by the opening and closing of the split 20 between the groove sections, thus eliminating splitting of the material.

Another object is the provision in such a coated wooden panel of a dovetail keying groove for the plastic material which is 25 composed of two communicating groove-sections formed in abutting corners of any two fastened or connected strips which form a portion or the whole of the base-board of the coated panel.

Another object of my invention is to 30 improve the method of making such surface grooves by forming in the abutting corners of the wooden strips comprising the base of the coated panel the opposite sections of the surface groove simultaneously with the formation of the dovetail tongues and grooves on and in abutting edges of such strips or boards forming the panel, whereby the assembling and fastening together of the dovetail tongued and grooved 40 edges will form the surface keying or dovetail groove for the plastic coat with substantially no additional expense for the grooving of the surface, and the plastic coat 45 may thereafter be applied and keyed by these grooves to produce the built-up coated panel.

With these and other objects in view, the invention comprises the combination of 50 members and arrangement of parts so combined as to coact and cooperate with each other in the performance of the functions and the accomplishment of the results herein contemplated, and comprises in one of its adaptations the species or preferred

form illustrated in the accompanying drawings, in which:—

Fig. 1 is a perspective view of a portion of the built-up composite balsa wood and cement panel embodying my invention; 60

Fig. 2 is a similar perspective view of one of the component balsa wood strips for building up the composite panel, a portion of which is shown in Fig. 1; and

Fig. 3 is a cross-section of a portion of 65 the panel embodying my invention having cement applied at opposite sides.

This invention is applicable to the formation of surface keying grooves for coats of plastic material in built-up insulation 70 panels composed of boards or strips of balsa wood or similar light wood having substantially the characteristics of balsa wood and will be described in relation to such composite panels, though it may be utilized 75 with other wood or similar base material.

Referring now to the accompanying drawings, 1 indicates a portion of a panel of balsa wood which is built up of strips or 80 boards 2 which are fastened together edge-wise, and by my invention, I form a surface keying groove 3 for the plastic coat 11 in the completed panel by providing at the corners between the surface 6 of the panel 1 and the abutting edges 4 and 5 of the 85 strips 2 which go to make up the panel, groove sections 7 and 8 respectively, so that when two strips 2 are assembled and fastened together with their edges abutting, the two parts of the groove on opposite sides 90 of the joint will communicate and form the completed groove 3 in the said surface 6 of the panel.

The strips 2 of which the panel is formed are preferably provided, as shown, on the 95 opposite abutting edges with intermeshing dovetail grooves 9 and projections 10. The making of such interconnectable dovetail grooves 9 and projections 10 is now accomplished with great accuracy in one operation on a suitable machine and in order to carry out my invention, it is only necessary 100 to add to the cutting tools of such machine additional cutters or cutting portions for the formation of the two sections or portions 7 and 8 of the surface grooves 3, whereupon the surface groove portions may be formed simultaneously with the intermeshable projections and grooves. When 110 the edges containing the intermeshable dove-

tail grooves 9 and projections 10 are slid relatively to each other to interlock or fasten the panel sections, boards or strips together, the opposite parts of the surface dovetail grooves 3 will intercommunicate at each joint to form the said completed surface dovetail groove 3.

The plastic coat 11, preferably composed of cement or plaster, is thereafter applied 10 and keyed to the surface by such surface dovetail groove or grooves 3.

The interlocking grooves 9 and projections 10 may, if desired, be slightly tapered relatively so that when the same are slid 15 relatively to each other for interconnection or interlocking, the tapered parts will cause a frictional gripping or driving fit which will result in a very close and fast connection or joint between the opposing boards, 20 strips or sections of the base and the formation of this connection or joint will, as aforesaid, simultaneously produce the dovetail surface groove 3 for keying to the surface of the panel at one or both sides thereof a 25 layer or layers 4 of plastic material, such as cement or plaster.

Any suitable adhesive may be applied to the abutting edges of the joints between the boards or strips 6 if desired to further fasten 30 the same together.

It will be evident that by the use of my invention a panel composed of a built-up base may be formed with much less expense than would be possible to produce such a 35 panel if the surface of the panel was grooved separately from the formation of the joints between the strips, boards or sections forming such panel base.

Having described my invention, I claim:—
40 1. A composite panel comprising a base built up of a plurality of sections abutting each other edgewise and fastened together, some of such abutting sections having in each of the adjacent corners between an 45 outer surface and the abutting edges, a substantially half section of a surface keying groove, whereby the assembling and fastening together of two abutting panel sections will form a complete surface keying groove, 50 and a plastic coat applied on the surface of the panel and keyed within such surface keying grooves.

2. A composite panel comprising a base built up of a plurality of wood sections abutting each other edgewise and fastened together, some of such abutting sections having in each of the adjacent corners between an outer surface and the abutting edges, a

substantially half section of surface keying grooves dovetail in conformation, whereby the assembling and fastening together of two abutting panel sections will form a complete surface dovetail groove and a plastic coat applied on the surface of the panel and keyed within such surface dovetail groove.

3. A composite panel comprising a base built up of a plurality of sections abutting each other edgewise and fastened together, some of such abutting sections having in the corners between an outer surface and the abutting edges, sections of surface keying grooves and also having formed within the abutting edges keying projections and grooves for interlocking the said abutting edges, whereby the assembling and fastening together of two abutting panel sections will form a complete surface keying groove, 75 and a plastic coat applied on the surface of the panel and keyed within such surface keying grooves.

4. A composite panel comprising a base built up of a plurality of wood sections abutting each other edgewise and fastened together, some of such abutting sections having in the corners between an outer surface and the abutting edges, sections of surface keying grooves, dovetail in conformation, and also having formed within the abutting edges keying projections and grooves for interlocking the said abutting edges, whereby the assembling and fastening together of two abutting panel sections will form a complete surface dovetail groove, and a plastic coat applied on the surface of the panel and keyed within such surface dovetail groove.

5. A composite insulation panel built up of a series of strips of balsa wood abutting each other edgewise and fastened together, some of such abutting sections having in each of the adjacent corners between an outer surface and the abutting edges, a substantially half section of a surface keying groove, dovetail in conformation, whereby the assembling and fastening together of two abutting panel sections will form a complete surface dovetail-groove and a plastic coat applied on the surface of the panel and keyed within such surface dovetail groove.

In witness whereof, I have signed my name to the foregoing specification in the presence of two subscribing witnesses.

HARRY W. BROADY.
